UNITED STATES PATENT OFFICE.

EUGENE D. ODELL AND ABIJAH JONES, OF DARIEN, ASSIGNORS OF ONE-HALF TO THE RACINE MALLEABLE AND WROUGHT IRON COMPANY, OF RACINE, WISCONSIN.

WHIP-SOCKET.

SPECIFICATION forming part of Letters Patent No. 445,126, dated January 20, 1891.

Application filed March 27, 1889. Serial No. 304,951. (No model.)

To all whom it may concern:

Be it known that we, EUGENE D. ODELL and ABIJAH JONES, citizens of the United States, residing at Darien, in the county of Walworth 5 and State of Wisconsin, have invented certain new and useful Improvements in Whip-Sockets and Line-Holders; and we do hereby declare the following to be a full, clear, and exact description of the invention, such as will 10 enable others skilled in the art to which it appertains to make and use the same.

Our invention relates to an automatic whip-socket; and its object is to provide a whip-socket so arranged and constructed that it is 15 inexpensive, very practical and effectual in operation, and provides a rein-holder into which the lines can be readily adjusted and easily removed. We attain this object by a certain construction and arrangement of 20 parts, fully described in this specification, and illustrated in the accompanying drawings, in which—

Figure 1 is a side view of the whip-socket. Figs. 2, 3, and 4 are detail views of parts to 25 which reference will be hereinafter made.

A, B, and C designate the parts of which the whip-socket is composed. The parts A and B are constructed, as shown in Figs. 2 and 3, respectively, with the inner side semicircular and flaring at the top, so as to be adapted 30 to receive and hold the whip. The lower end of the part A is made with the cap a, which has a recess upon its inner side, in which one end of the spiral spring D is located. Above said cap there is an offset with 35 a view of making the part A adapt itself to the parts B and C, so that they all can be pivoted together. With this object in view the part A is constructed with the circular 40 projection a', having the orifice a², through which the pivot b passes. We attach special importance to this construction of the part A. The offset above referred to, the cap a, and the projection a' are all novel features 45 that enable us to pivot the parts of which the whip-socket is composed near the bottom and to locate the spiral spring D close to the pivotal hinge, so that it operates very effectually, and neither the pivot nor spiral spring inter-

fere in the least with the whip. Besides being thus located, it is impossible for them to get out of order or cease to be effectual in operation.

In the center of the part A there are two clamps a³, by which the whip-socket is secured 50 to the dash-board of the vehicle. This is accomplished simply by removing the screws a⁵ and placing the braces or clamps a⁶ upon the opposite side of the dash-board and then adjusting the screws through the openings in the 55 braces a⁶, thence through the dash-board into the orifices in the ends of the ears a⁷.

C represents that part of the whip-socket which serves, in co-operation with the other parts, as a rein-holder, and it is made with 60 the cap c upon its lower end, which corresponds to the cap a upon the lower end of the part A. The cap c also has a recess upon the inner side, and in the recesses upon the inner sides of the caps a and c the ends of the 65 spiral spring D are adjusted and securely held in position. The part C also has a projection c', in which there is an orifice c², the purpose of which will be hereinafter explained.

It will be observed that the sides of the lower end of the part B are circular, having a cavity in the center of same, into which the projecting parts a' and c', (respectively, of the parts A and C,) are adapted, and into which they are placed and securely pivoted by means of the pivot b, which passes through the orifice a² of the part A, the orifices b² of the part B, and the orifice c² of the part C, thereby fastening securely the three parts together 80 and making a pivotal hinge upon which said parts work, and which is controlled by the spiral spring D, which causes said parts to readily adjust themselves and securely hold any whip or line that may be placed in the 85 whip-socket.

We attach special importance to the location and arrangement of this pivotal hinge and the spiral spring D, by means of which an automatic whip socket and line-holder are 90 combined in one, and so arranged that each element is absolutely essential to the perfection of our invention.

What we claim, and desire to secure by Letters Patent, is—

In a whip-socket, the combination of the parts A, B, and C, pivoted near their lower ends by the pivot b, the parts A and C having the caps a and c upon the lower ends of same, with recesses upon their inner sides, and the spiral spring D, having its ends located in the recesses upon the inner side of

said caps, substantially as described, and for the purpose set forth.

In testimony whereof we affix our signatures in presence of two witnesses.

EUGENE D. ODELL.
ABIJAH JONES.
